SUPERCHARGER

Charles A. Kutcher, Sheridan, Wyo.

Application February 12, 1937, Serial No. 125,513

2 Claims. (Cl. 230—131)

My invention relates generally to a supercharger for internal combustion engines, and particularly to a supercharger for connection to the carburetor of a gasoline engine, which supercharger acts at low speed as a vaporizer, and at high speed as a supercharging device for supplying the intake manifold with fuel mixture under pressure and in a high degree of vaporization, and an important object of my invention is to provide an efficient and practical arrangement of this character.

Another important object of my invention is to provide improvements over the subject matter of my Patent No. 2,012,570 by providing for more thorough and efficient intermixture of air and gas, so as to produce a more highly combustible fuel mixture.

Another important object of my invention is to provide more efficient bearing lubricating means for the rotor of the supercharger.

Other important objects of my invention will be apparent from a reading of the following description taken in connection with the drawings, wherein for purposes of illustration I have shown a preferred embodiment of my invention.

In the drawings:—

Figure 1 is a general longitudinal sectional view taken through an embodiment of my invention.

Figure 2 is a transverse vertical sectional view taken through Figure 1.

Figure 3 is a sectional detail.

Referring in detail to the drawings, the numeral 5 generally designates the casing of the supercharger which is substantially circular and has a substantially tangential lower neck portion 6 which is provided with a flange 7 including openings 8 to receive bolts for fastening the casing onto the intake manifold of the engine (not shown).

Mounted eccentrically on one side of the casing 5 by means of screws or bolts 9 is a flange 10 formed on the tubular bearing support 11 which projects substantially axially from the mentioned side of the casing. The barrel 11 has a reduced extension 12 which extends through an opening 13 in the side 14 of the casing and has set in a counterbored portion 15 a ball or roller bearing arrangement 16. The counterbored portion 15 is larger than the main bore portion 17 which leads into an enlarged bore portion 18 at the outer end of the barrel 11 to define a shoulder 19 against which abuts the roller or ball bearing structure 20. Sliding in the bore portion 18 is an annular ring 21 which

has a beveled outer face 22 which is engaged by a conformably shaped annular packing 23. The rotor shaft 24 turns in a conforming opening in the packing 23 and in the ring 21 and has a reduced portion 25 turning in the ball bearings 16 and 20, respectively. A thrust washer 26 engages the inner side of the ball bearing 16 and one face of the hub portion 27 of the rotor plate 28, and a nut 29 on the threaded portion 30 of the said shaft engages the opposite face of the hub portion 27 in a manner to lock the disk or plate 28 on the shaft 24. The shaft 24 is suitably operatively connected to the internal combustion engine.

A lubricating plug 31 is removable from the top of the barrel 11 and this plug ordinarily closes a small passage 32 which opens into the bore of the barrel 11 whereby lubricant may be introduced for lubricating the bearings 16 and 20, these bearings being kept separated by a sleeve 33 disposed on the reduced portion 25 of the shaft.

A pressure and suction equalizing passage 34 opens into the chamber 35 defined by the right hand side of the bearing 20 and the cut-out left hand end of the annulus 21 and opens into the interior of the casing 5. The necessity and desirability for this equalizer passage rises from the fact that when the engine idles, it produces a strong suction of air in the casing and when the engine is speeded up it produces a pressure in the casing. This phenomenon is due to the difference of speed of the rotor to be described in relation to the speed of the engine and the suction produced by the pistons of the engine. Without such an equalizing means the oil or grease utilized to lubricate the bearing would be forced out by suction or pressure. The equalizer passage makes the pressure and the suction equal at opposite ends of the bearing housing 11 and prevents disturbance of the lubricant therein. A closure plate 36 is fastened by screws 37 to the outer end of the bearing housing 11.

The described side 14 of the casing is recessed as indicated by the numeral 38 and the plain disk portion of the rotor plate 28 turns within this recess as shown in Figure 1 of the drawings, the hub portion 27 of this disk surrounding the inner end of the extension 12 of the bearing housing as shown.

Axially opposite the shaft 24 is the annulus 40 which is set in an opening 41 in the side 42 of the casing and this annulus extends somewhat inwardly beyond the wall 42 to prevent raw gas from dropping down along the side of the casing and to deliver this raw gas to the blades of the

5 rotor. Surrounding the opening 41 is the curved intake conduit 43 which has a flange 44 on its upper end provided with bolt holes 45 enabling connecting it to the discharge of the carbureter (not shown). The wall 42 of the casing is a removable plate which is fastened in place by means of bolts or screws 46 which engages a flange 47 extending radially inwardly from the rim 48 of the casing.

10 The present embodiment of the invention contemplates a rotor having three series of blades denominated 49, 50 and 51, respectively, mounted on the rotor disk or plate 28 and two stationary series of blades denominated 52 and 53, respectively, the latter being fastened to and projecting from the removable plate 42 and extending between adjacent ones of the movable series of blades as clearly shown in Figure 1 of the drawings.

15 20 On the blade series 49, 50 and 51 the blades are flat and elongated rectangular and disposed at an acute angle with respect to any diameter of the circles which they compose and these blades 49', 50', and 51', respectively, have one end fastened by suitable means to the plain portion of the rotor plate or disk 28 and to their opposite ends they have fastened respective annuli 54, 55 and 56.

25 The stationary series of plates 52 and 53 have 30 blades which are somewhat narrower than the rotary blades and the stationary blades 52' and 53' are arranged in alignment with diameters of the circles in which they are disposed, and these last-mentioned blades have one end fastened in 35 a suitable manner to the removable side 42 of the housing 5 and their opposite ends suitably secured to respective annuli 57 and 58. As shown in Figure 1 of the drawings the free ends of the stationary blades approach quite closely to the 40 adjacent face of the rotor plate 28, while the free ends of the movable blades approach very closely to the adjacent face of the removable plate 42. By increasing the number of rotary and stationary blades and increasing the reactive relation 45 thereof, more effective atomization and supercharging of the fuel intaken from the carbureter is achieved by the present invention. Further, the provisions for lubricating the shaft thereof render the lubricant free from influence 50 of suction and pressure, so that the lubricant is no longer disturbed, and a more satisfactorily operating and longer lived apparatus results.

55 Although I have shown and described herein

a preferred embodiment of my invention, it is to be definitely understood that I do not desire to limit the application of the invention thereto, and any change or changes may be made in the materials and in the structure and arrangement of the parts, within the spirit of the invention and the scope of the subjoined claims.

Having described the invention what is claimed is:—

1. In a supercharger of the character described, 10 a casing having a substantially tangential discharge, a tubular bearing support mounted eccentrically on one side of the casing and having a portion extending into the casing, a shaft having an end located in the support, the said shaft 15 terminating slightly beyond the inner end of the support, bearings in the support and engaging parts of said end of the shaft, an inlet member connected with the other side of the casing and having its discharge end or mouth in axial alignment with the inner end of the support, stationary circular series of blades on the last-mentioned side of the casing, a rotor having an inwardly extending hub fitting over the inner end of the support and connected with the terminal of the 20 shaft, movable circular series of blades carried by the rotor and in effective relation to said stationary series of blades.

2. In a supercharger of the character described, 25 a casing having a substantially tangential discharge, a tubular bearing support mounted eccentrically on one side of the casing and having a portion extending into the casing, a shaft having an end located in the support, the said shaft 30 terminating slightly beyond the inner end of the support, bearings in the support and engaging parts of said end of the shaft, an inlet member connected with the other side of the casing and having its discharge end or mouth in axial alignment with the inner end of the support, stationary 35 circular series of blades on the last-mentioned side of the casing, a rotor having an inwardly extending hub fitting over the inner end of the support and connected with the terminal of the shaft, movable circular series of blades carried by the 40 rotor and in effective relation to said stationary 45 series of blades, and a member connected with the mouth of the inlet member and forming a continuation of the walls of the inlet member and extending into the casing to a point inwardly of 50 the free ends of the blades of the rotor.

CHARLES A. KUTCHER.
